UNITED STATES PATENT OFFICE.

EARL G. WHELPLEY, OF CLEVELAND, OHIO, ASSIGNOR TO THE SHEA-WHELPLEY CONSTRUCTION COMPANY, OF CLEVELAND, OHIO, A CORPORATION OF OHIO.

CHECKERWORK CONSTRUCTION.

Application filed March 9, 1928. Serial No. 260,298.

This invention relates to checker-work construction comprising a plurality of bricks assembled in such manner as to provide a plurality of ducts therethrough for heated gases; 5 also to a brick which is specially constructed and adapted for use in the erection of such constructions. The brick and the checker work construction of which it forms a part are especially adapted for use in hot blast stoves, 10 and the embodiment of the invention shown herein will be discussed in connection with its use in such stoves, although it will be understood that I do not thereby limit the invention to such specific use.

15 The general purpose and object of the invention is to provide a brick which can be conveniently and readily assembled with other like bricks to provide a checker work construction having a maximum heating surface; also to provide a checker work construction, including the special construction of brick referred to hereinbefore, which can be quickly and economically assembled.

20 A still further object of the invention is to provide a brick of the character described which will lend itself to such quick and economical assembly; which can be conveniently interlocked with other like bricks; and which will stand up in operation with a minimum 25 liability of breakage.

I accomplish the foregoing objects in and through the construction and arrangement of parts shown in the drawings, wherein Fig. 1 represents a detail in plan of part of a hot 30 blast stove equipped with checker work and checker-work bricks constructed and arranged in accordance with my invention; Fig. 2 a detail in perspective of one of the bricks, the convergence of certain parts thereof to a common axis being indicated by dot-and-dash lines; and Fig. 3 a detail in section corresponding to the line 3—3 of Fig. 1.

35 Referring first to the individual bricks of which the checker work is composed, each brick is of T-shape and comprises a base 1 and a central stem or mid-feather 2. The outer face 3 of each brick constitutes a section of a cylinder the axis of which is indicated by the line $a-c$ on Fig. 1; and one of the radii extending from the axis to such surface is indicated at b . The sides 4 of the base of each brick are in radial planes extending outwardly from the axis $a-a$, the lines c, c, c, c indicating radii drawn from the upper and 40 lower edges of the sides to the axis $a-a$.

The sides 5 of the stem or mid-feather 2 also converge toward and meet at the same axis $a-a$, the lines d, d, d, d indicating radii drawn from the upper and lower edges of the sides to the axis $a-a$. Each stem or mid-feather 2 is provided with a central radial rib 6 and a central radial depression 7, the rib being shown at the top of the brick and the recess at the bottom of the brick, although this arrangement may evidently be reversed without 50 affecting the spirit of the invention. Furthermore, the inner end 2^a of each mid-feather is concave, to enable it to fit more or less closely against the outer surface of an adjacent brick or against the inner cylindrical wall of 55 a hot blast stove. Each side 5 of the mid-feather is connected with the base 1 by means of a concave surface 8.

In constructing a checker work from bricks such as shown and described, and assuming 75 that the checker work is to be interposed between the inner cylindrical wall 9 of a hot blast stove and the outer wall (not shown), I have found it practicable to use bricks of 80 the same size, and with the same curvature of the face 3 and the same convergence of the sides 4 and 5 for the formation of the first three concentric vertical checker-work walls, changing such curvature and convergence in each successive series of three concentric 85 walls.

Referring in particular to Fig. 1, a denotes one end of the axis or center of the hot blast stove, said axis corresponding to the axis $a-a$ of Fig. 2. The bricks in the first wall 90 surrounding the wall 9 are so constructed that their sides 4 and 5 correspond with radial planes extending from the axis a , and the outer face 3 of each brick corresponds to a section of a cylinder the axis of which is at 95 a . The sides 4 of the bricks comprising the innermost wall will contact through their entire extent. When assembled and interlocked in the manner indicated in Figs. 1 and 3, vertical flues 10 will be formed between the wall 9 and the sides of the mid-feathers and the inner sides of the bases of the bricks, the depth of each wall and the depth of the flues depending upon the particular installation 100 in which the checker work is to be used.

105 In laying the next outer wall of bricks, the sides 4 will not contact throughout their extent, due to the fact that they converge toward and, if extended, would meet at points e on a circle f described from a as a center and 110

having a radius equal to the depth of one of said bricks. There will be a slight V formed between the sides 4 of adjacent bricks, but their outer portions will be in contact. Furthermore, the surface formed between the outer faces 3 of the bricks will not constitute a true cylinder, but will approximate thereto.

The sides 4 of the bricks in the third wall converge toward and, if extended, would meet 10 at points *g* on the circle *h* described from the axis *a*, and at a distance from such axis equal to the depth of two bricks. In this case, the surface formed by the outer faces of the bricks will still approximate a cylinder, but 15 the V-shaped spaces between the faces 4, 4 of adjacent bricks will be somewhat larger than in the preceding wall.

In starting on the next series of three walls, I employ a new set of bricks, the sides 4, 4 20 of which are concentric with the axis *a* and, if extended, would intersect at the said axis; so also would the sides 5, 5 of the mid-feathers. The second and third walls in the second series will be laid in the same manner as 25 the second and third walls in the first series; and so on for succeeding series of walls.

By virtue of the construction and manner of assembling the bricks, I am enabled to obtain a maximum exposed heating surface 30 through each flue 10; to provide a construction which will enable the bricks to be assembled quickly and to form a stable construction. I am also enabled to provide a checker-work construction comprising a plurality of concentric walls, which construction 35 possesses the necessary stability but without the necessity for interlocking the said walls. Where walls are so interlocked, there is danger of disruption through expansion and contraction 40 due to variations in temperature between the inner and outer walls. This difficulty is entirely obviated by my construction. Furthermore, the manner of forming the mid-feathers, with the concave surfaces 45 8 connecting the same to the bases of the bricks, strengthens the mid-feathers at their intersections with the bases and minimizes the danger of breakage. However, should any brick happen to break, it will be locked 50 against displacement by the bricks above and below the same.

Having thus described my invention, what I claim is:

1. In a hot blast stove, the combination, 55 with a cylindrical inner stove wall, of a plurality of walls of bricks surrounding the inner stove wall, each brick being substantially T-shaped and having a base the outer surface whereof is cylindrical, the sides of the said 60 bricks converging toward the center of said stove and each brick having a mid-feather projecting toward the center of said stove, the ends of the mid-feathers in the innermost wall 65 engaging the inner stove wall and the mid-feathers in other walls engaging the outer cy-

lindrical surfaces of the bricks constituting the wall therewithin.

2. In a hot blast stove, the combination, 70 with a cylindrical inner stove wall, of a plurality of walls of bricks surrounding the said stove wall, each brick being substantially T-shaped and having a base the outer surface whereof is cylindrical, the sides of the said 75 bricks converging toward the center of said stove and each brick having a mid-feather projecting toward the center of said stove, the mid-feathers in the innermost wall engaging the inner stove wall and the mid-feathers in other walls engaging the outer cylindrical 80 surfaces of the bricks constituting the wall therewithin, the mid-feathers of each of said 85 bricks being slightly concave at the inner end thereof.

3. In a hot blast stove, the combination, 85 with a cylindrical inner stove wall, of a plurality of walls of bricks surrounding the said stove wall, each brick being substantially T-shaped and having a base the outer surface whereof is cylindrical, the sides of the said 90 bricks converging toward the center of said stove and each brick having a mid-feather projecting toward the center of said stove, the sides of each mid-feather also converging toward the center of the stove, the mid-feathers in the innermost wall engaging the 95 said wall and the mid-feathers in other walls engaging the outer cylindrical surfaces of the bricks constituting the wall therewithin.

4. In a hot blast stove, the combination, 100 with a cylindrical inner stove wall, of a plurality of walls of bricks surrounding said stove wall, each brick being substantially T-shaped and having a base the outer surface whereof is cylindrical, the bricks in two or 105 more concentric walls being identical in construction and each having sides converging toward the center of the stove, the sides of the bricks constituting the innermost wall coinciding with radial planes extending from the center of the stove and each brick having a 110 mid-feather projecting toward the center of the stove and the sides of which converge at the same angle as the sides of the base of such brick, the mid-feathers in the innermost wall 115 engaging the said stove wall and the mid-feathers in other walls engaging the outer cylindrical surfaces of the bricks constituting the wall therewithin.

5. In a hot blast stove, the combination, 120 with a cylindrical inner stove wall, of a series of walls of bricks surrounding said stove wall and each series comprising two or more walls, each brick being substantially T-shaped and having a base the outer surface 125 whereof is cylindrical, the bricks in each series being identical in construction and each having sides converging toward the center of the stove, the sides of the bricks constituting the innermost wall of each series coinciding with radial planes extending from the 130

- center of the stove and each brick in such wall having a mid-feather projecting toward the center of the stove and the sides of which converge at the same angle as the sides of the 5 base of such brick, the mid-feathers in the innermost wall engaging the said stove wall and the mid-feathers in other walls engaging the outer cylindrical surfaces of the bricks constituting the wall therewithin.
- 10 6. A brick for the purpose specified, the said brick being of substantially T-shape and having a mid-feather and a base, the outer surface of the base being cylindrical and the sides of the base and the sides of the mid- 15 feather converging toward a common line toward which the mid-feather projects.
7. A brick for the purpose specified, the said brick being of substantially T-shape and having a mid-feather and a base, the outer 20 surface of the base being cylindrical and the sides of the base and the side of the mid-

feather converging toward a common line toward which the mid-feather projects, the inner end of the mid-feather being slightly concave.

8. A brick for the purpose specified, the said brick being of substantially T-shape and having a mid-feather and a base, the outer surface of the base being cylindrical and the sides of the base and the sides of the mid- 30 feather converging toward a common line toward which the mid-feather projects, the sides of the mid-feather being connected with the base by concave surfaces and the mid-feather having a top surface and a bottom 35 surface, the said surfaces being provided the one with a central radial rib and the other with a central radial recess.

In testimony whereof, I hereunto affix my signature.

EARL G. WHELPLEY.
